(57) **ABSTRACT**

A new *Verbena* plant particularly distinguished by purple
flowers with a tiny white eye and an upright habit with a
compact, round shape, is disclosed.

1 Drawing Sheet

1

Genus and species: *Verbena x hybrida*.
Variety denomination: 'KLEVP20064'.

BACKGROUND OF THE NEW PLANT

The present invention comprises a new and distinct variety of *Verbena*, botanically known as *Verbena x hybrida*, and hereinafter referred to by the variety name 'KLEVP20064'. 'KLEVP20064' originated from a cross-pollination conducted in November 2015 in Cobbitty, New South Wales, Australia between the proprietary female *Verbena* variety '15.5074' (unpatented), and the proprietary male *Verbena* variety '15.5022' (unpatented).

The seeds from the cross were sown and plants were grown for evaluation, where an individual plant designated 'KLEVP20064' was selected from the group of plants in Cobbitty, New South Wales, Australia in October 2016.

In October 2016, 'KLEVP20064' was first vegetatively propagated by vegetative cuttings in Cobbitty, New South Wales, Australia. 'KLEVP20064' was found to reproduce true to type in successive generations of asexual propagation via vegetative stem cuttings.

SUMMARY

The following are the most outstanding and distinguishing characteristics of this new variety when grown under normal horticultural practices in Cobbitty, New South Wales, Australia.

1. Purple flowers with a tiny, white eye; and
2. An upright habit with a compact, round shape.

DESCRIPTION OF THE PHOTOGRAPH

This new *Verbena* plant is illustrated by the accompanying photograph which shows the plant's overall plant habit including form, foliage, and flowers. The photograph is of a plant approximately twelve weeks old grown indoors in

2

Stuttgart, Germany in April 2020. The colors shown are as true as can be reasonably obtained by conventional photographic procedures.

5 DESCRIPTION OF THE NEW VARIETY

The following detailed descriptions set forth the distinctive characteristics of 'KLEVP20064'. The data which define these characteristics were collected from asexual 10 reproductions carried out in Latina, Italy. Data was collected on three-month-old plants grown in a greenhouse in Latina, Italy in 2019. Color references are to The R.H.S. Colour Chart of The Royal Horticultural Society of London (R.H.S.), 5th edition (2007).

15 **Classification:**

Family.—Verbenaceae.
Botanical.—*Verbena x hybrida*.
Common.—*Verbena*.
Designation.—'KLEVP20064'.

20 **Parentage:**

Female parent.—'15.5074' (unpatented).
Male parent.—'15.5022' (unpatented).

25 **Plant:**

Growth and branching habit.—Upright with compact round shape.

Height (from top of soil).—22.0 cm.

Width (horizontal plant diameter).—32.0 cm.

Time to produce a finished flowering plant.—Approximately 8 weeks.

Time to initiate and develop roots.—2 weeks.

Root description.—White, RHS 155B, fine and fibrous roots.

30 **Stems:**

Number of branches per plant.—More than 27.

Length.—20.0 cm.

Diameter.—0.24 cm.

Internode length.—Approximately 1.8 cm.

Color.—RHS 139D.

COMPARISON WITH PARENTAL LINES AND KNOWN VARIETY

TABLE 1

Comparison with Parental Lines			
Characteristic	'KLEVP20064'	Female parent	Male parent
Flower color	Purple with tiny white eye	Purple with big white eye	Purple without eye

‘KLEVP20064’ is most similar to the commercial *Verbena* ‘KLEVP15616’ (U.S. Plant Pat. No. 28,320). Differences between the varieties are described in Table 2.

TABLE 2

45	Comparison with Similar Variety		
	Characteristic	'KLEVP20064'	'KLEVP15616'
50	Growth habit	Upright with compact round shape	Upright
	Flower color	Purple with tiny white eye	Pink with colored eye

I claim:

1. A new and distinct variety of *Verbena* plant designated 'KLEVPA20064' as illustrated and described herein.
